CLAIM

The ornamental design for a printing blanket mounting bar, as shown and described.

DESCRIPTION

FIG. 1 is a perspective view of a printing blanket mounting bar showing our new design;

FIG. 2 is an end elevational view thereof, the opposite end being a mirror image of the end shown;

FIG. 3 is a top plan view thereof;

FIG. 4 is a front elevational view thereof;

FIG. 5 is a bottom plan view thereof;

FIG. 6 is a rear elevational view thereof; and,

FIG. 7 is a fragmentary perspective view of one end thereof.
